UNITED STATES PATENT OFFICE

CYRUS J. HOLLAND, OF CHICAGO, ILLINOIS

FRICTION DRAFT GEAR

Application filed March 6, 1926. Serial No. 92,849.

The invention relates to draft gear for rail-way cars.

The principal object of the invention, generally stated, is to provide a novel friction draft gear embodying a peculiar arrangement of springs and friction elements capable of taking up the shock during buff and also under draft.

An important object of the invention is the provision of a draft gear including a system of intercalated spring elements providing cushioning means, means being also provided for bringing these elements into frictional engagement.

The object of the invention, more specifically stated, is to provide a friction draft gear embodying a combination of intercalated leaf springs combined with cam or wedge means for forcing them into engagement and providing not only cushioning means or resilience but also frictional resistance to relative longitudinal movement under buff, other spring means being provided for effecting release of the intercalated spring elements when the buffing strain is relieved.

A still further object of the invention is to provide a friction draft means capable of being used in the standard size gear pocket so that it may replace ordinary or standard equipment without necessitating any material changes in the construction of the parts, the release spring being, however, located outwardly of the center sills of the car in order that the intercalated spring members and wedge or cam compressing means therefor may be accommodated within the draft gear pocket.

Another object of the invention is to provide a friction draft gear adapted for use in connection with draft rigging including draft keys which are horizontally disposed and which are movably mounted along slots in the center sills and in cheek plates attached thereto, the travel of the keys being in accord with normal requirements or standards.

Yet another object of the invention is to provide a gear of this type in which the parts are so arranged and combined as to permit free spring travel for a certain distance to take care of small vibrations which occur in

the draft gear in train movement, the intercalated spring plates being flexed slightly along with the compression of the springs during the first portion of the movement, the intercalated plates being, however, provided mainly to give the frictional resistance and the other spring elements providing not only the release but also the means for taking up the first portion of the movement.

Generally speaking, the invention consists in the provision of a shock absorbing device including the combination of a flexible intercalated plate friction resistance member, a force applying member, and means for transferring energy from the force applying member to the flexible friction resistance member.

A still further object of the invention is to provide a draft gear embodying peculiarly mounted and arranged cam or wedge operated rockable means cooperating with flexed intercalated spring plates for applying pressure thereto under buff, the pressure tending not only to straighten the flexed plates and consequently provide resilience but also create frictional resistance between the plates as they are moved relatively in a longitudinal direction.

To the attainment of the foregoing and other objects and advantages the invention preferably consists in the details of construction and the arrangement and combination of parts to be hereinafter more fully described and claimed, and illustrated in the accompanying drawings in which:

Figure 1 is a horizontal section through a draft gear constructed in accordance with my invention, the parts being shown in normal or draft position, the intercalated flexed plates being in open position.

Figure 2 is a similar view showing the position of the parts under buff, the intercalated spring plates being shown in engagement and the other spring members being compressed.

Figure 3 is a vertical longitudinal section through the gear taken on the line 3-3 of Figure 1.

Figure 4 is a vertical cross sectional view through the gear taken on the line 4-4 of Figure 1, and

Figure 5 is a vertical section through the gear taken on the line 5—5 of Figure 1 and illustrating the cam or wedge means cooperating with the flexed spring plates.

Referring more particularly to the drawings the numeral 1 designates the center sills of a car slotted in the usual manner and having secured thereto cheek plates 2 formed with elongated slots 3 for the accommodation of horizontally disposed spaced keys 4, the cheek plates being represented as provided with front stops 5 and back stops 6 which may be formed integrally therewith or separately therefrom and attached thereto, whichever is preferred. The cushioning mechanism between the center sills may be so formed as to readily cooperate with any one of the standard dimensions of gear pocket. Located within this pocket are forward and rear followers 7 and 8, the former of which is formed in opposite sides with slots 9 of greater length than the width of the front key and the latter of which may be formed with slots 10 of substantially the same length as the rear key, the reason for the difference being hereinafter explained.

Located within the confines of the followers are sets of intercalated spring plates 11 and 12, the sets being disposed at opposite sides of the longitudinal center line or axis of the gear and those in each set being flexed outwardly as clearly indicated in Figure 1. The springs 11 are formed with slots 13 for the passage of the forward key, the slots being of greater length than the key to permit a certain amount of free movement thereof prior to the engagement of the follower with the spring 11. The springs 12 are slotted at 14 but the size of the slots is such that the usual key will be accommodated rather snugly to avoid lost motion. Each of the spring plates 11 and 12 is shown as having its end portions bent around or folded, the purpose being to provide a large bearing area between the spring elements and the force applying member, though it is of course conceivable that some alternative arrangement of an equivalent nature may be provided if found desirable for any reason.

Located outwardly of the intercalated spring plates are lateral pressure applying members 15 slotted at their rear ends as indicated at 16 for the accommodation of the rear key, the slots being of sufficient size to permit lateral swinging movement of these members with respect to the spring plates and center sills without danger of binding at any point or points. These members bear against the normally convex outer surfaces of the outermost spring plates 12 and the rear extremities may be formed with lateral extensions 17 fulcruming within curved recesses 18 at the inner corners of the rear follower 8. At their intermediate portions the members 15 may be reduced in thickness to lighten the

structure and the forward ends are formed at their outer sides with rearwardly and outwardly curved surfaces 19 against which bear rollers 20 which, in turn, coat with oppositely arranged curved surfaces 21 on the inner sides of the rear portion of the front follower 7, the arrangement being such that upon relative movement of the followers towards each other the pressure applying members 15 will be swung toward each other for applying pressure to the flexed spring plates 11 and 12, resulting in developing resilience and creating frictional resistance between the plates as they are moved relatively.

In addition to the intercalated flexed spring plates, I make use of other spring means which, on account of the lack of space within the draft gear pocket are located outwardly of the center sills. In the present instance I have shown abutment members 22 mounted on the projecting outer ends of the keys as by means of substantially U-shaped collars 23 which embracingly engage the keys and which are secured as for instance by means of vertical pins 24 passing through alining holes in the collars and keys, any suitable means being provided for preventing displacement of the pins such, for instance, as by the simple expedient of providing the upper ends with lateral extensions 25. The abutment members 22 are provided centrally with extensions 26 which fit within the end portions of helical springs 27 about which are disposed, in encircling relation thereto, other helical springs 28 preferably considerably heavier and stronger than the first mentioned.

Of course the rigging of which the present gear forms a part includes the usual vertical yoke 29 and coupler 30, both of which elements are represented by dot and dash lines instead of in detail inasmuch as they really form no part of the present invention.

Under normal circumstances the keys are of course separated to the widest possible extent. Under either buff or draft there is of course a tendency for the followers to move relatively, resulting in corresponding movement of the keys which is permitted owing to the provision of the slots 3 in the check plates. Whenever the keys are moved toward each other, or one moved toward the other, the springs 27 and 28 will be compressed and will provide resilience giving the proper cushioning effect. Owing to the elongation of the slots 13 in the flexed spring plates 11 there is a certain amount of movement of the front key possible without causing movement of the plates, the movement being, in actual practice, approximately one-half inch to permit the usual vibration or slight movement incidental to train travel without affecting the position of the spring plates. When the movement becomes greater it is evident that the interfitting spring

plates will slide together into telescoped relation as disclosed in Figure 2, the springs 27 and 28 being of course simultaneously compressed. As the front follower 7 moves rearwardly, under buffing strain or as the rear follower 8 moves forwardly under draft, there is of course movement of the pressure applying members 15 with respect to the front follower and owing to the engagement of the curved surfaces 19 and 21 with the rollers 20 it is clear that the members 15 will be rocked or swung inwardly upon the extensions 17 as fulcrums, the result being the application of lateral pressure to the intercalated spring plates. This pressure acts against the natural flexure of the plates and produces a cushioning effect in addition to forcing the plates together for causing frictional resistance to the sliding or telescoping movement thereof. On the release, the first movement due to the pressure of the friction plates, or tendency thereof to flex, together with the expansive effect of the coil springs will be that the key will move the follower or roller end back the distance provided for permitting free movement, in actual practice one-half inch as above explained, so as to take up the preliminary spring travel. This follower, then having received an appreciable impetus, and still having pressure against it, through the rollers from the flexed intercalated plates, will continue to travel back until it strikes the key, whereupon the pressure against the spring plates will have been relieved to such an extent that the release springs 27 and 28 may then pull the intercalated plates apart by means of the key. The release action is not identically the same under draft as under buff as in the latter instance it is merely necessary to move the front follower, while in the former it is necessary to move the rear follower together with the interior mechanism of the gear.

A draft gear constructed in accordance with this invention will be highly satisfactory and advantageous inasmuch as it meets all of the requirements of present day service in point of certainty of operation and positive durability even under the most adverse conditions. It is thought that the construction, operation and advantages will be readily apparent to one skilled in the art without further explanation.

While I have shown and described the preferred embodiment of the invention, it should be understood that the disclosure is merely illustrative as the right is reserved to make all such changes and modifications as will increase the adaptability or widen the field of utility of the structure, provided such variations constitute no departure from the spirit of the invention or the scope of the claims hereunto appended.

Having thus described the invention, I claim:

1. In a shock absorbing device, the combination of a flexible intercalated bowed plate friction resistance member, a force applying member, means located outwardly of the resistance member for transferring energy from the force applying member inwardly to the flexible friction resistance member, and means located outwardly of said resistance member for effecting release.

2. In a shock absorbing device, the combination of initially flexed intercalated plate cushioning and friction resistance members, means for applying force thereto longitudinally thereof, and rocker means operated by said means for applying lateral pressure, to the resistance member against flexure thereof, and spring means opposing said force for effecting release.

3. In a shock absorbing device, the combination of a laterally flexible member of intercalated normally flexed plate arrangement, means for applying pressure thereto longitudinally thereof, means directly opposing the application of longitudinal pressure, and cam means acting to convert the longitudinal pressure to lateral pressure inwardly against the intercalated members for developing frictional resistance to longitudinal movement thereof.

4. In a shock absorbing device, normally flexed intercalated cushioning and friction resistance means providing yielding resistance to lateral compression, means for applying longitudinal pressure thereupon, means for opposing the longitudinal pressure applying means, and rocker means acted upon by the longitudinal pressure means for developing lateral pressure upon the first means and creating spring and frictional resistance.

5. In a shock absorbing device, the combination of flexed intercalated plate means, means acting longitudinally upon said plate means for sliding the same in interfitting relation, cam and rocker operated means actuated upon the application of longitudinal pressure for developing lateral pressure upon said first means and producing frictional resistance to sliding movement thereof, and spring means opposing sliding movement of the plate means and providing for release.

6. In a shock absorbing device, the combination of relatively movable members, sets of intercalated flexed plate members located between said members, means for moving said members, and rockable elements fulcrumed at one of said first named members and bearing against opposite sides of said flexed plates and actuated by the other of said first named members for applying lateral pressure thereto during closure and separate release means.

7. In a shock absorbing device, the combination of members movable toward each other, sets of inter-fitting flexed plates located

between said members and arranged in slide-
able relation, pressure applying members ful-
crumed at one of said members and bearing
against opposite sides of the sets of plates,
and cam means at the other of said first
named members cooperating with said pres-
sure applying members for moving the same
toward each other and bringing lateral pres-
sure upon the plates as they move longitudi-
nally and separate spring release means.
10

8. In a shock absorbing device, the combi-
nation of members movable toward each other,
sets of inter-fitting flexed plates located
between said members and arranged in slide-
able relation, pressure applying members ful-
crumed at one of said members and bearings
against opposite sides of the sets of plates,
cam means at the other of said first named
members cooperating with said pressure ap-
plying members for moving the same toward
each other and bringing lateral pressure
upon the plates as they move longitudinally,
and combined cushioning and release springs
opposing movement of said first named mem-
bers toward each other.
25

9. In a railway draft gear, forward and
rear followers, sets of intercalated flexed
spring plates arranged between said follow-
ers, keys carried by the followers and en-
gaging said spring plates, spring means in-
terposed between the keys, and pressure ap-
plying members located at opposite sides of
the spring plates and operatively connected
with one follower to be moved laterally
thereby into compressing and friction pro-
ducing engagement with said spring plates.
35

10. In a railway car draft gear, the car
having center sills carrying front and back
stops, forward and rear followers located be-
tween the sills and stops, intercalated flexed
spring plates located between the followers,
draft keys engaging the followers and pass-
ing through and beyond the center sills, means
between the sills operatively engaged by a
follower for applying lateral pressure to the
spring plates during longitudinal movement
thereof, and cushioning means located be-
tween the keys outwardly of said sills.
45

11. In a draft gear for railway cars hav-
ing center sills equipped with front and back
stops, the combination with a yoke and cou-
pler, of front and rear followers between the
stops, intercalated flexed spring plates lo-
cated between the followers and arranged in
slideable relation, draft keys passing through
the followers and spring plates, cushioning
means engaging the keys, and pressure apply-
ing means located between the sills and co-
operating with the followers to apply pres-
sure laterally upon the spring plates.
55

12. In a draft gear for railway cars hav-
ing center sills equipped with front and back
stops, the combination with a yoke and cou-
pler, of front and rear followers between
the stops, intercalated flexed spring plates lo-

cated between the followers and arranged in
slideable relation, draft keys passing through
the followers and spring plates, cushioning
means engaging the keys, pressure applying
means located between the sills and cooperat-
ing with the followers to apply pressure lat-
erally upon the spring plates, and means for
permitting limited free movement of one fol-
lower with respect to the spring plates.
70

13. In a draft gear for railway cars hav-
ing center sills equipped with front and back
stops, the combination with a yoke and cou-
pler, of front and rear followers between the
stops, intercalated flexed spring plates lo-
cated between the followers and arranged in
slideable relation, draft keys passing through
the followers and spring plates, cushioning
means engaging the keys, and pressure apply-
ing means located between the sills and co-
operating with the followers to apply pres-
sure laterally upon the spring plates, the
front follower and adjacent ends of the flexed
plates being slotted for the accommodation
of the forward key, the slots being of a
length permitting limited free movement of
the front follower with respect to the spring
plates.
75

14. In a draft gear for railway cars, front
and rear followers, cushioning means oppos-
ing movement thereof, intercalated flexed
spring plates located between the followers,
means engaging one follower and the adjac-
ent ends of the spring plates for insuring
simultaneous longitudinal movement there-
of, and means engaging the other follower
and adapted to engage the adjacent spring
plates subsequent to limited movement, and
means cooperating with the followers for
applying lateral pressure to the spring plates
during closure thereof as the result of rela-
tive longitudinal movement.
90

15. In a draft gear for railway cars, front
and rear followers, cushioning means oppos-
ing movement thereof, intercalated flexed
spring plates located between the followers,
means engaging one follower and the adjac-
ent ends of the spring plates for insuring
simultaneous longitudinal movement there-
of, means engaging the other follower and
adapted to engage the adjacent spring plates
subsequent to limited movement, means co-
operating with the followers for applying
lateral pressure to the spring plates during
closure thereof as the result of relative longi-
tudinal movement, said means including
rockable arms engaging the spring plates
and having cam surfaces, cam surfaces on
one follower, and rollers between the cam
surfaces.
110

16. In a shock absorbing device, the com-
bination of flexed intercalated friction plates
arranged in slideable relation, rocker means
for applying pressure laterally upon said
friction plates, means for initially moving
said rocker means alone inwardly and then
125

additionally moving the same simultaneously with longitudinal movement of the plates, and release spring means.

17. In a shock absorbing mechanism, the combination of sets of flexed intercalated friction plates, means pivoted outwardly of said friction plates and engageable therewith for applying lateral pressure thereto, cam means for moving said means inwardly 10 into compressing engagement with the friction plates, and a release spring.

18. In a shock absorbing device, the combination of sets of oppositely flexed intercalated friction plates arranged in slidable 15 relation, means mounted for rocking movement outwardly of and engaging against the opposite sides of said sets of friction plates for applying pressure thereto, and cam means engaging said means for moving the same 20 into compressive relation with the friction plates, and release spring rocking means.

In testimony whereof I affix my signature.
CYRUS J. HOLLAND.
